UNITED STATES PATENT OFFICE.

CHESTER D. AINSWORTH, OF WOLLASTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

ELECTROMAGNET.

Application filed September 1, 1922. Serial No. 585,672.

This invention relates to electro-magnets particularly adapted, although not necessarily limited, to operate electric switches and has for its object to improve the construction and operation of such electro-magnets.

The magnet structure set forth herewith is disclosed in my following co-pending applications:

Serial No. 535,220, filed February 2, 1922;
Serial No. 522,227, filed December 14, 1921;

Serial No. 585,672, filed Sept. 1, 1922.

Fig. 1 is a side elevation of an electric switch having an electro-magnet embodying my invention.

Fig. 2 is a side elevation of the electro-magnet.

Fig. 3 is a plan view of Fig. 2.

Fig. 4 is a front view of Fig. 2 with parts of the operating mechanism removed.

Fig. 5 is a front view of the magnet frame.

Fig. 6 is a detail of the plunger and operating lever.

Fig. 7 is a sectional elevation of the magnet frame along line 7—7 of Fig. 3.

Fig. 8 is a sectional elevation of the cover plate along line 7—7 of Fig. 3.

Fig. 9 is a rear view of the magnet frame of Fig. 7.

Fig. 10 is a bottom view of Fig. 1, looking upward.

Fig. 11 is a view illustrating the magnet combined with a shaft adapted to operate a gang of electric switches simultaneously.

Fig. 12 is a sectional detail of the face plate and plunger of the tripping coil, along line 7—7 of Fig. 3.

Fig. 13 is a detail of the plunger of the tripping coil.

The electro-magnet structure embodying my invention is of the iron-clad solenoid type and includes a magnet frame or shell 15 formed of magnetic material, as cast iron, and which, as an integral structure, is adapted to contain the solenoid adapted to effect the closing of the switch, and a separate solenoid adapted to control the tripping, or opening, of the switch. For this purpose, the frame is formed with the cylindrically-shaped recess 16 adapted to receive a switch-closing solenoid A, and a second and smaller cylindrically-shaped recess 17 arranged beneath and at right angles to said first recess and adapted to receive the switch tripping

solenoid B. The inner wall 18 of the closing solenoid recess 16 is formed with the axial and cylindrically-shaped projection 19 adapted to enter and form a pole piece for the closing solenoid, and said pole-piece is here shown as integrally formed with the rear wall 18, although it may be otherwise arranged.

The rear face of the wall 18 is formed with a raised portion or base 20 whereby the rear wall, in the vicinity of the pole piece, is of increased cross-sectional area and the remainder of the wall whereby to avoid concentration of magnetic flux, and, consequently, increased reluctance, of the frame at this point.

The front face of the magnet frame is formed with a plurality of slots 21 disposed at various angularly-related points about its periphery and which extend into the closing solenoid recess 16 and are adapted to receive the solenoid leads, and the arrangement provides means by which the solenoid leads may be brought out of the frame at a point most convenient for connection with a control circuit.

The rear face of said wall 18 is or may be formed with the corner bosses 22 adapted to form feet which are adapted to engage the frame of a switch, or other support, and bolt-receiving apertures 23 may be formed in the magnet frame which extend through said bosses.

The rear wall 25 of the tripping solenoid recess 17 also is or may be integrally formed with an axial, inwardly-projecting and cylindrically-shaped pole-piece 26 which is adapted to enter the tripping solenoid. The outer face of the side wall of said recess also is or may be formed with a plurality of angularly related slots 27 adapted to receive the leads of the closing solenoid. Such slots as are not occupied by solenoid leads may serve as vent passages for the solenoid recess; and the same is also true for the closing solenoid recess.

The magnet frame is or may be formed with the substantially flat top face 28 adapted to receive an auxiliary or inducting switch hereinafter to be described.

The closing solenoid recess 16 with the solenoid therein is covered by the face plate 30 which is disposed over the recess and secured to the walls of the magnet frame or

housing by the bolts 31 which are or may be threaded into the magnet frame. Said face plate is made of magnetic material and forms part of the magnetic circuit of the 5 solenoid. Said face plate is adapted to support components of the operating mechanism and it and the attaching means therefor are so arranged that the face plate may be secured to the magnet frame in a plurality of 10 angularly related positions, and especially in relatively reversed positions, whereby to permit the magnet to operate a switch or other apparatus through mechanism disposed mainly above, or mainly below, the closing 15 solenoid, as desired.

Said face plate is or may be formed with a hub or boss 33 projecting from its inner face and said hub is adapted to extend into the solenoid. The face plate and hub are 20 formed with the cylindrical passage 34 through which the armature or plunger 35 is movably extended into the solenoid. Said hub 33 provides means to reduce the concentration of the magnetic flux between the face plate and the plunger.

Said plunger 35 is or may be pivotally connected to the spaced levers 36 which are pivoted, by the pin 38, to the lugs 37, or it 30 may be one lug, extended from an edge of the outer face of the face plate. For this purpose, the extended end-portion of said plunger may be formed with the opposed flat side-faces 39 which are disposed between the spaced levers 36 and a pin 40 may 35 pivotally connect said plunger and levers. Said plunger is or may be provided with an end slot 41 which may receive a single lever, not shown, in place of the dual levers 36 when desired, and said single lever may be 40 pivotally received between said lugs 37.

Said face plate also is or may be formed or provided with the four pairs of spaced and outwardly extended lugs 42 disposed at the upper and lower portions of the face 45 plate and on opposite sides of the levers 36 for the purpose of supporting an arm adapted to connect the operating mechanism of the magnet structure with an auxiliary switch, as will hereinafter be described.

Said levers 36 extend downwardly below the plunger 35 and a pin 44 may connect the ends thereof, and a roller 45 may be disposed on said pin between said levers and adapted to bear against and engage suitable 55 operating mechanism carried by the magnet frame and disposed below the closing magnets.

The operating mechanism includes the operating shaft 46 which is horizontally disposed below the face plate 30 and at right angles to the levers 36 and is rotatably supported in bearings 47 which are integrally formed with and extend forwardly from the 60 opposite side walls of the tripping solenoid portion of the magnet frame. Said bearings 65

may be provided with the removable bearing caps 48.

An arm 49 is fixed to said shaft between said bearings and extends upwardly toward said levers 36, and may be formed with the 70 flat face 50 which is adapted to be engaged by the roller 45 carried by said levers 36 and forced inwardly to rotate the operating shaft 46 in a clockwise direction, Fig. 2, when the closing solenoid is energized. Preferably 75 means are provided whereby loosely to connect said arm and levers positively and prevent the displacement of said levers from operative relation from said arm when the mechanism is released by the tripping sole- 80 noid, and restored rapidly to a position corresponding to the open position of a switch connected therewith. Said means may comprise the links 52 which are or may be loosely pivoted on the pin 44 carried by said levers 85 42 and disposed on opposite sides of the roller 45 and also disposed on opposite sides of said arm 49 and loosely pivotally connected therewith by the pin 53. Said links preferably are sufficiently loosely connected with 90 said pins as to permit the operative engagement of the roller 45 and arm 49 and yet limit the extent of separation of said members.

A socket member 55 is or may be fixed to 95 said operating shaft, preferably on one side of a bearing 47 therefor, and may have a recess 56 adapted to removably receive a handle, or it may be otherwise arranged, whereby to permit the rotation of the shaft 100 by hand to operate the switch or other apparatus connected with said shaft.

Said arm 49 is or may be integral with a second arm 60 which is extended downwardly below said shaft and is adapted to effect the locking of the mechanism in and the release thereof from switch-closed position through connection with the tripping solenoid and associated mechanism.

The tripping solenoid is enclosed in its 110 recess in the magnet frame by the face plate 61 which is secured to said frame over the recess by suitable means as the bolts 62. Said face plate is or may be similar in construction to the face plate for the closing solenoid and includes the boss 63 having the aperture 64 in which the armature or plunger 65 of the tripping solenoid is movably received. Said plunger 65 is cylindrical in formation and is or may be formed with 115 the lug 66 at its lower face. A U-shaped strap-member 67 is secured to said lug and depends downwardly from the plunger and is adapted to provide means by which the plunger is operatively connected with a locking and tripping lever, or the connection 120 may be otherwise formed.

Said face plate 61 is or may be formed or provided with the spaced depending lugs 68 adapted to receive and support a pin 69 125

in front of said plunger 65, and a latch roller 70 is or may be loosely received on said pin between said lugs.

A locking and tripping lever 72 is received in a slot formed in said depending arm 60 connected to said operating shaft and is or may be pivotally connected to said arm by suitable means as the pin 73. Said lever is extended rearwardly between the lugs 68 of the tripping solenoid face plate and over the roller 70 thereof and the end of said lever is received between the strap-member 67 of the plunger of the tripping solenoid. The lower face of said lever 72 is formed with the notch 74 therein adapted to receive the latch roller 70 and the wall 74^a of said notch is adapted to be substantially tangential to the arc of movement of the lever at the roller, whereby said roller is effective to hold the lever in locking position and consequently hold the operating mechanism in switch-closed position. When, however, said tripping solenoid is energized, the plunger 65 thereof is forcibly attracted upwardly and consequently engages said lever 72 and raises it upwardly above the roller 70 whereupon the operating mechanism is moved to open position by the switch mechanism, or by other means, and the lever 72 slides rearwardly within the strap member of the plunger 65.

Said magnet structure is particularly adapted to operate the switch illustrated in Fig. 1 and may be attached directly to the frame 75 of said switch. Said switch is characterized by having internally disposed operating mechanism and an operating shaft 75^a which is extended through and laterally beyond said casing, on one or both sides thereof, as may be desirable. A depending arm 75^b is or may be fixed to said shaft and a rod 75^c may be pivotally connected therewith. The outer end of said rod may be slidably received in the guide member 75^d of the switch casing. A spring 75^e may encircle said rod and press against said guide member and an abutment 75^f of the rod and form means by which the switch is moved into open position, and said spring may also move the operating mechanism of the magnet structure to open position.

The operating shaft 46 of the magnet structure may have an arm 80 fixed thereto on one side, or it may be opposite sides, of the magnet frame and said arm may be pivotally connected with a rod 81 which also is pivotally connected with the arm 75^b of the switch whereby operably to connect the operating mechanism of the magnet structure with the switch. When the closing solenoid is energized, the plunger 35 thereof is forcibly attracted and moves the levers 36 into engagement with the arm 49 of the operating shaft 50, whereby to rotate said shaft to compress the spring 75^e and close

the switch. The switch and the operating mechanism are locked in closed position by engagement of the locking and tripping lever 72 with the roller 70. When the tripping solenoid is energized said lever 72 is raised from engagement with the roller 70 and said spring 75^e operates to move the switch and the operating mechanism of the magnet structure into open position.

Said operating shaft 46 may extend beyond the magnet frame in both directions for connection with other apparatus, if desired.

An insulating plate 85, or it may be two such plates, may be secured to a side of said magnet frame and have terminal connectors or binding posts 86 adapted to be connected with the terminals of the closing and tripping solenoids and also with the respective circuit leads for said solenoids.

An auxiliary or signalling switch is usually or may be associated with the main switch to control remotely disposed indicating devices and indicate the open or closed condition of the switch. The auxiliary switch 90 may be secured on the flat top face 23 of the magnet frame and may have a movable member 91 which is adapted to be actuated by the magnet structure in accordance with the operation of the main switch. For this purpose, a lever 92 may be pivotally connected with said movable member 91 and pivotally received on the pin 93 between a pair of lugs 42 of the cover plate 30. Said lever may extend below said lugs and be formed with a slot 94 in which is received the reduced end portion of the pin 40, which pin serves to connect the plunger of the closing solenoid with its levers 36, or it may otherwise be connected with said levers. It is obvious that said lever 92 will be reciprocated to control the auxiliary switch as the operating mechanism of the magnet structure is operated to close and open the main switch.

Said lugs 42 are or may be provided with a plurality of pivot-pin holes 95 by which the leverage of the lever 92 and consequently the throw thereof may be varied whereby to adapt the magnet structure for various types of auxiliary switches. Said lever 92 is adapted to be pivotally supported by any of said pairs of lugs, and be connected with either end-portion of said pin 40.

Fig. 6 shows a relatively reversed position of the face plate 30 and the levers 36 and, as thus arranged, the closing solenoid may control a switch by over-head mechanism not shown.

An important object of the invention is the construction and arrangement of the magnet structure by which the closing magnet may act directly on and rotate a shaft extended between and connected to a gang of switches, whereby to operate said switches

simultaneously. Fig. 11 illustrates such an arrangement. As shown, the operating shaft 46^a, which corresponds to the shaft 46, is or may be extended on both sides of the magnet structure and the ends thereof may be supported in fixed bearings 100.

Arms 101 may be fixed in spaced relation on said shaft and are adapted to be connected through suitable linkages, not shown, 10 with the switch mechanisms. If desired, a plurality of magnet structures may be connected with the same line of shafting.

The construction illustrated herewith may be modified without departing from the 15 spirit of the invention.

I claim:

1. An electro-magnet comprising the combination of a magnet frame, a solenoid therein, a plunger operable in the solenoid, a pivoted lever connected with said plunger intermediate its length and pivoted to said frame at one side of said plunger, and a rotatably supported operating shaft disposed at the other side of said plunger and having an arm arranged for engagement 20 with said pivoted lever said shaft having an extension disposed at one side of said arm and having a second arm on said extension.

2. An electro-magnet comprising the combination of a magnet frame having a recess, a solenoid received in said recess, a face-plate secured removably to said magnet frame over the recess and solenoid comprising a cover for the recess, a plunger movably received in said solenoid and face-plate, a lever pivoted to said face-plate at one side of said plunger and connected with said plunger, and a rotatably supported operating shaft disposed at the other side of said plunger and having an arm arranged for engagement with said pivoted lever.

3. An electro-magnet comprising the combination of an integral magnet frame having recesses therein, closing and tripping solenoids received in said recesses, an operating shaft rotatably supported in bearings of said magnet frame between said solenoids and having a laterally extended arm, a plunger operated by said closing solenoid, a lever pivoted to said magnet frame at one side of said plunger and connected with said plunger and extended thereacross for engagement with the arm of said shaft, whereby to rotate the shaft, locking means associated with said shaft, and a plunger operable in said tripping solenoid arranged to control said locking means.

4. An electro-magnet comprising the combination of a magnet frame, a rotatably supported operating shaft having a laterally extended arm, a pivoted armature structure arranged to bear against said arm, whereby to rotate said shaft, and means loosely connecting said armature structure positively

with said shaft, comprising links loosely connected with said arm and armature.

5. An electro-magnet comprising the combination of a magnet frame, a rotatably supported operating shaft having a laterally extended arm, a pivoted armature structure arranged to bear against said arm, whereby to rotate said shaft, and means loosely connecting said armature structure positively with said shaft comprising links loosely connected with said arm and armature adjacent the point of engagement of said arm and armature.

6. An electro-magnet comprising the combination of a magnet frame having a recess, a solenoid received therein, a face-plate secured to said magnet frame over the recess and solenoid comprising a cover for said recess, a plunger movable in said face-plate and solenoid, a pivoted depending lever carried by said face-plate and a connected with said plunger, an operating shaft carried by bearings of said magnet frame below said lever and having an upstanding arm disposed between its bearings and arranged to be engaged by said pivoted lever, and means loosely connecting said arm and lever positively.

7. An electro-magnet comprising the combination of a closing magnet, an armature therefor, an operating shaft, means operably connecting said armature and shaft, and means to hold said shaft releasably against rotation including a fixed projection, a pivoted lever carried by and movable with said shaft arranged to engage and be held by said fixed projection, whereby to hold said shaft from rotation, and a tripping magnet arranged to move said pivoted lever from engagement with said fixed projection.

8. An electro-magnet comprising the combination of a closing magnet, an armature therefor, an operating shaft, means operably connecting said armature and shaft, and means to hold said shaft releasably against rotation including a fixed projection, a pivoted lever carried by said shaft arranged to engage and be held by said fixed projection, a tripping solenoid having a plunger arranged to move said pivoted lever from engagement with said fixed projection, and means loosely connecting said plunger and pivoted lever arranged to admit of a transverse movement of said pivoted lever relative to and in engagement with said plunger.

9. An electro-magnet comprising the combination of a closing magnet, an armature therefor including a depending lever, an operating shaft, means operably connecting said armature and operating shaft including an arm upstanding from said shaft and disposed for engagement with said lever, and means to hold said shaft releasably against rotation comprising a second arm depending from said shaft, a fixed projection, a locking

lever pivoted to said depending arm arranged to engage said fixed projection releasingly, and a tripping solenoid having a plunger loosely connected with said locking device lever arranged to move it from locking engagement with said fixed projection.

10. An electro-magnet comprising the combination of a closing magnet, an armature therefor, an operating shaft, means operably connecting said armature and operating shaft, and means to hold said shaft releasingly against rotation comprising an arm extended laterally from said shaft, a fixed projection, a locking lever pivoted to said arm arranged to engage said fixed projection releasingly, and a tripping solenoid having a lever-operating plunger formed with a transverse passage therethrough in which said locking lever is loosely received.

20. 11. An electro-magnet comprising the combination of a magnet frame, a closing magnet having an armature, a rotatably supported operating shaft operably connected with said armature, said magnet frame having a recess, a tripping solenoid received in said recess, a face-plate secured to said magnet frame over said recess and solenoid, a roller carried by said face-plate, a locking lever pivotally carried by said operating shaft arranged to engage said roller releasingly, and a plunger operated by said solenoid having means loosely connecting it with said locking lever whereby to release it from locking engagement with said projection.

25. 12. An electro-magnet comprising the combination of a magnet frame having a recess, a closing solenoid received in said recess, a face-plate secured to said magnet frame over said recess and solenoid, a lever pivoted to said face-plate, a plunger movably received in said face-plate and solenoid and pivotally connected with said lever, an operating shaft rotatably supported by said magnet frame having a laterally extended arm arranged to be engaged by said pivoted lever, said operating shaft also having a second laterally extended arm, a latch lever pivoted to and carried by said second arm, said magnet frame having a second recess, a tripping solenoid received therein, a face plate secured to said frame over said recess and tripping solenoid, said face-plate having a locking projection arranged to be releasingly engaged by said latch lever, and a plunger movably received in said face plate and closing solenoid having means to engage said latch lever and move it from locking engagement with said locking projection.

30. 13. An electro-magnet comprising the combination of a magnet frame, having a recess, a closing solenoid received in said recess, a face-plate secured to said magnet frame over said recess and solenoid, a lever

pivoted to said face-plate, a plunger movably received in said face-plate and solenoid and pivotally connected with said lever, an operating shaft rotatably supported by said magnet frame having a laterally extended arm arranged to be engaged by said pivoted lever, said operating shaft also having a second laterally extended arm, a locking lever pivoted to and carried by said second arm, said magnet frame having a second recess, a tripping solenoid received therein, a face-plate secured to said frame over said recess and tripping solenoid, said face plate having a locking projection arranged to be releasingly engaged by said locking lever, and a plunger movably received in said face plate and closing solenoid having means to engage said locking lever and move it from locking engagement with said locking projection, said means arranged loosely to engage said locking lever and permit transverse movements of said lever relative to said plunger.

35. 14. An electro-magnet having the combination of a magnet frame formed with a recess therein, a closing solenoid received in said recess, a face-plate secured removably to said magnet frame over said recess and closing solenoid and comprising a cover for both, an operating shaft rotatably supported by said magnet frame below said face-plate, said shaft having an upwardly extended arm, a lever pivoted to said face-plate at the upper end thereof and extended downward for engagement with said arm, a plunger connected with said lever below its pivoted end and movably received in said face-plate and solenoid, and electrically controlled locking and releasing means for said operating shaft.

40. 15. An electro-magnet comprising the combination of an integral magnet frame having two recesses therein arranged at substantially right angles, a closing solenoid and a tripping solenoid received in said recesses, face-plates removably covering said recesses and solenoids, said magnet frame having integral spaced bearing supports laterally extended below said closing solenoid, an operating shaft rotatable received in said supports, an armature for said closing solenoid pivotally supported by the closing-solenoid face-plate and operably connected with said operating shaft intermediate said bearing supports, an armature for said tripping solenoid, and locking and releasing means for said operating shaft associated with said tripping-solenoid armature and including a projection depending below and carried by the face plate of said tripping solenoid, and a latch-lever carried by said shaft arranged to ride over said projection and engage said tripping solenoid.

45. 16. An electro-magnet comprising a magnet frame having a recess therein, a solenoid

- received in said recess, an armature for said solenoid, a face-plate arranged to cover said recess and solenoid, an operating lever connected with said armature and pivoted to 5 said face plate at one side of said armature, and means to secure said face-plate to said magnet frame in a plurality of angularly-related positions, whereby to permit said operating lever to operate mechanism disposed 10 in various angularly related positions.
17. An electro-magnet structure comprising the combination of a magnet frame having a solenoid and an armature, an operating shaft rotatably supported in and extended on opposite sides of said magnet frame, 15 said shaft having means operably connecting it with said armature, bearing supports arranged to rotatably support the extended ends of said shaft, and a plurality of spaced 20 connecting members carried by said shaft arranged for operative connection with the operating mechanisms of a gang of switches.
18. An electro-magnet comprising a magnet frame having a recess, a solenoid received therein, a face-plate secured to said magnet frame over said recess and solenoid and comprising a cover for both, a lever pivoted to said frame, a plunger connected with said lever and movable within said 25 solenoid, a second lever, and a plurality of angularly-related lugs projecting from said face plate each adapted pivotally to receive and support said lever.
19. An electro-magnet comprising a magnet frame having a recess, a solenoid received therein, a face-plate carried by said magnet frame over said recess and solenoid, an operating lever pivoted to said face plate, 30 a plunger connected to said lever and operable within the solenoid, a second lever independently pivoted to said face plate, and means to operate both levers simultaneously.

20. An electro-magnet comprising a magnet frame having a recess, a solenoid received therein, a face plate carried by said magnet frame over said recess and solenoid, an operating lever pivoted to said face plate, a plunger connected to said lever and operable within the solenoid, an arm pivoted to 45 said face plate adjacent and connected loosely with said lever, and an auxiliary switch carried by said magnet frame having its movable switch member connected with said arm.

21. An electro-magnet comprising the combination of a magnet frame having closing and tripping magnets, an armature for said closing magnet, a rotatably supported operating shaft operably connected with said armature, an arm pivotally carried by said operating shaft, and an armature for said tripping magnet carried by said pivoted arm.

22. An electro-magnet comprising the combination of a magnet frame having a closing solenoid and a tripping solenoid, a rotatably supported operating shaft, a plunger for said closing solenoid operably connected with said operating shaft, an arm pivotally carried by said operating shaft, 70 and a plunger for said tripping solenoid carried by said pivoted arm.

23. An electro-magnet comprising the combination of a magnet frame having a closing solenoid and a tripping solenoid, a rotatably supported operating shaft, a plunger for said closing solenoid operably connected with said operating shaft, an arm eccentrically pivoted to said operating shaft, and a plunger for said tripping solenoid 80 carried by said pivoted arm.

In testimony whereof, I have signed my name to this specification.

CHESTER D. AINSWORTH.
